UNITED STATES PATENT OFFICE

HENRY W. MENARD, OF LOS ANGELES, CALIFORNIA

DESIGN FOR AN ORNAMENTAL TREE

Application filed August 24, 1931. Serial No. 40,913. Term of patent 3½ years.

To all whom it may concern:

Be it known that I, HENRY W. MENARD, a citizen of the United States, and resident of Los Angeles, California, have invented a new, original, and ornamental Design for an Ornamental Tree, of which the following is a specification, reference being had to the accompanying drawing, forming a part hereof.

The drawing is a perspective of the tree.

I claim:

The ornamental design for an article of manufacture comprising an ornamental tree, substantially as shown.

HENRY W. MENARD.
